C. TSCHIFFELY

COLLAPSIBLE TUBE

Filed Nov. 3, 1921

Inventor
Claude Tschiffely

Attorney

UNITED STATES PATENT OFFICE.

CLAUDE TSCHIFFELY, OF WASHINGTON, DISTRICT OF COLUMBIA.

COLLAPSIBLE TUBE.

Application filed November 3, 1921. Serial No. 512,528.

To all whom it may concern:

Be it known that I, CLAUDE TSCHIFFELY, a citizen of the United States, residing at Washington, in the District of Columbia, 5 have invented certain new and useful Improvements in Collapsible Tubes, of which the following is a specification.

My said invention relates to a collapsible tube for liquids or semi-liquids such as tooth 10 paste, cold cream, mucilage and the like, and it is an object of the invention to provide an improved top for such containers.

A further object of the invention is to provide an improved neck on the tube, said 15 tube and neck having cooperative means to prevent ready disengagement of the cap from the tube.

Referring to the accompanying drawings which are made a part hereof and on which 20 similar reference characters indicate similar parts.

Figure 1 is an elevation of a collapsible tube and its cap, the latter being in position for attachment to the tube,

25 Figure 2 is a top view in closed position.

Figure 3 a horizontal section through the cap and the neck of the tube, and

Figure 4 is a partial vertical section of the device.

30 Figure 5 is a sectional view through the cap when removed from the tube showing the manner in which the top of the cap bulges downwardly.

In the drawings 10 indicates a collapsible 35 tube of conventional form having at its upper end a threaded neck 11. An internally threaded cap 12 is adapted to be screwed on the neck, the cap being externally milled or roughened in usual fashion. The cap has an 40 aperture at 13 adapted to register in one position with a corresponding aperture in said neck, the latter being otherwise closed at the top by a transversely extending portion or plate 14. The top of the cap about the aperture 45 13 is downwardly beveled as shown at 15 to form a cutting edge adapted to lie closely against the plate 14, and the upper part of the cap may bulge downward as shown in Figure 5 and be slightly resilient to maintain 50 contact between the same and the plate 14. When the apertures are brought together by screwing down the cap the bulged top of the cap is flattened by the top of the tube as shown in Figure 4. When the cap is unscrewed the resiliency of the top of the cap

will restore the bulge and insure close contact between the top of the tube and the cap so as to obtain a clean cutting action. This cutting edge is intended to sever the material extruded from the tube from that remaining and if such material is sufficiently hard it will make a clean cut therethrough separating the extruded part from the remaining part and at the same time preventing waste of the material. Preferably the 60 thread will be of low pitch so that the up or down movement of the cap during the partial revolution necessary to bring the two apertures into or out of register will be very limited in extent.

A portion of the thread 11 is cut away at one side of the neck as indicated at 16 and after the cap has been screwed down thereon a portion of the cap is punched in as at 17. This portion forms an abutment which 70 75 will permit the cap to be rotated through a sector, here shown as approximately a quarter revolution, but will strike against the end of the remaining thread and prevent further revolution. In ordinary cases the 80 material of the cap and the tube is, however, sufficiently soft so that the internal abutment at 17 will crumble if sufficient force is used and thus permit removal of the cap should this be desirable.

Various modifications of my device will suggest themselves to those skilled in the art and therefore I do not limit myself to what is here shown and described but only as indicated in the appended claims.

Having thus fully described my said invention, what I claim as new and desire to secure by Letters Patent, is:

1. A dispensing device having a threaded neck, a threaded cap connected thereto, said neck and cap having corresponding apertures and means for placing the apertured top of the cap under a tension whenever the top is screwed on the cap to register the said apertures, substantially as set forth.

2. A collapsible tube having a threaded neck, a threaded cap therefor, a segment of one of the threads being omitted and an inwardly projecting abutment on the other member adapted to move in the space left 105 by said omitted thread segment, substantially as set forth.

3. A collapsible tube having an externally threaded neck, a cap having internal threads for engagement with said neck, a portion of 110

- one of said threads being omitted, and an abutment on the opposing member adapted to move in the space left by the omitted thread, substantially as set forth.
5. A dispensing device having a threaded neck, a threaded cap connected thereto the top of said cap being curved inwardly and provided with an aperture formed with a cutting edge said neck having a flat face
- 10 engaging said curved portion of the cap and provided with an aperture, and means incident to the rotation of the cap on the neck to register said apertures and distort and place under tension the top of the cap, substantially as set forth.
- 15 5. A container having a neck of unbroken

cylindrical contour at the inside and having a helical outer thread a segment of one convolution of said thread being omitted, and a threaded cap having an abutment projecting into the space left by said omitted thread thereby limiting the rotation of the cap, substantially as set forth.

In witness whereof, I have hereunto set my hand and seal at Washington, District 25 of Columbia, this 3rd day of November, A. D. nineteen hundred and twenty-one.

CLAUDE TSCHIFFELY.
